(57) **CLAIM**

We claim the ornamental design for a clamping member, as shown and described.

DESCRIPTION

The present application is related to U.S. Ser. No. 13/708,287 and U.S. Ser. No. 29/439,187, each filed on even date here-with.

FIG. 1 is an isometric view of our new clamping member design;

FIG. 2 is a front elevational view thereof shown in FIG. 1;
FIG. 3 is a right elevational view thereof shown in FIG. 1;
FIG. 4 is a rear elevational view thereof shown in FIG. 1;
FIG. 5 is a left elevational view thereof shown in FIG. 1;
FIG. 6 is a top view thereof shown in FIG. 1; and,
FIG. 7 is a bottom view thereof shown in FIG. 1.

The broken line portion of the figure drawings is included to show unclaimed subject matter only and forms no part of the claimed design.
